(No Model.)

W. S. & C. H. MILLER.
BICYCLE LAMP.

No. 588,460.

Patented Aug. 17 1897.

UNITED STATES PATENT OFFICE.

WILLIAM S. MILLER AND CLINTON H. MILLER, OF PHILADELPHIA,
PENNSYLVANIA.

BICYCLE-LAMP.

SPECIFICATION forming part of Letters Patent No. 588,460, dated August 17, 1897.

Application filed April 26, 1897, Serial No. 633,905. (No model.)

To all whom it may concern:

Be it known that we, WILLIAM S. MILLER and CLINTON H. MILLER, citizens of the United States, residing in the city and county 5 of Philadelphia, State of Pennsylvania, have invented a new and useful Improvement in Bicycle-Lamps, which improvement is fully set forth in the following specification and accompanying drawings.

10 Our invention relates to an improved construction of lamp or lantern which is especially adapted to be carried on bicycles or other vehicles; and it consists of a novel manner of supporting the mantle employed and 15 guiding and sustaining the wick-tube when the parts are in assembled position.

It further consists of novel details of construction, all as will be hereinafter set forth, and fully pointed out in the claims.

20 Figure 1 represents a front elevation of bicycle-lamp embodying our invention. Fig. 2 represents a section on line xx , Fig. 1. Fig. 3 represents a perspective view of a clamping device employed. Fig. 4 represents a perspective view of a mantle employed, the same being shown in detached position. Fig. 5 represents a perspective view of a frame employed to support the mantle and guide and sustain the upper end of the wick-tube, said 30 frame being shown in detached position.

Similar letters of reference indicate corresponding parts in the figures.

Referring to the drawings, A designates a bicycle-lamp, the same having a body portion 35 B, to which is secured the base or reservoir C, from which latter the wick-tube D arises, said wick-tube passing through an opening E in the reflector F.

G designates a frame for guiding and retaining the upper portion of the wick-tube, said frame consisting of the body portion or sleeve H and the deflected portion or flange J, which is adapted to be secured to a suitable portion of the reflector F.

45 K designates a ring secured to the upper portion of the body H and adapted to receive the upper end of the wick-tube D, the same being provided with a channel L, as will be best understood from Fig. 5.

50 M designates a band which is supported upon the ring K when the parts are assem-

bled, and has arising therefrom the wires or threads Q, of platinum or other similar material, the upper extremities of said wires connecting with the perforated cap P, the whole 55 forming a mantle N, the construction of which will be clearly understood from Fig. 4.

R designates an outlet-flue for the egress of the products of combustion, said tube being supported at its upper extremity upon the 60 hood Z, which is attached to the body B by means of the neck Y, said hood being provided with the openings A', which communicate with the atmosphere.

T designates a clamp which surrounds the 65 tube R, the members of said clamp being held together by means of a screw U or other fastening device.

V designates a rod depending from the clamp E, said rod or arm having attached to 70 the lower portion thereof the ring W, which holds in position the lower portion of the chimney X, while the upper portion of the latter is held in position between the chimney R and the clamp T, said tube X passing through 75 the opening S in the reflector, and being constructed of mica, isinglass, or other transparent similar material.

B' designates openings in the body B of the lamp in communication with the atmosphere. 80

It will be seen that the ring K supports the mantle and serves to retain in position the upper end of the wick-tube B, and by reason of the channel or slot L a free draft-passage is obtained, and, furthermore, by slightly 85 concaving the body portion H of the frame G the latter will serve as a guide for the upper end of the wick-tube when the parts are in the act of being assembled, it being understood that the base C is preferably detachably 90 secured to the body B.

By the employment of the clamp T, the rod V, and the ring W a convenient means is afforded for holding the upper and lower portions of the flue X in position with respect to 95 the tube R.

If necessary, we provide the ring K with depending flaring fingers, forming the guides A', which prevent the wick-tube from striking the said ring.

It will be apparent from the foregoing that the increased draft created by the rapid pro-

gression of the lamp or vehicle on which it is carried will create a very bright flame, and by reason of the channel in the ring a draft is assured and there is a very small liability of the lamp being extinguished.

Having thus described our invention, what we claim as new, and desire to secure by Letters Patent, is—

1. A lantern provided with a frame, means for supporting the same within the lantern, and a ring attached to the body portion of said frame, said ring being adapted to retain in position the upper extremity of a wick-tube and the lower portion of a mantle.
- 15 2. In a bicycle-lamp, a reflector having secured thereto the flange J, the body portion H attached to said flange and a channeled ring K attached to said body portion, the inner portion of said ring being adapted to guide and retain the upper portion of a wick-tube, while the outer portion of said ring is adapted to support the lower portion of a mantle.
- 20 3. In a bicycle-lamp, a mantle suitably supported, a flue leading therefrom to the exterior of the lamp, a chimney of transparent mate-

rial in engagement with said flue and inclosing said mantle, a clamp surrounding said flue and chimney, an arm depending from said clamp and a ring attached to said arm and engaging the lower portion of said chimney. 30

4. In a lantern, a frame on the interior thereof, means for supporting the same, and a ring on said frame adapted to retain in position a wick-tube and supporting a mantle.

5. In a lantern, a frame on the interior thereof, means for supporting the same, a mantle, a wick-tube, and a ring on said frame adapted to retain in position said wick-tube and said mantle and having a channel therethrough. 35

6. In a lantern, a frame, means for supporting the same within said lantern, a ring attached to said frame and adapted to retain in position said wick-tube and said mantle, and having a channel therethrough and guides attached to or forming part of the said ring. 40
